United States Patent Office.

HARVEY A. MOORE, E. OTIS FRINK, AND SAMUEL C. FRINK, OF INDIANAPOLIS, INDIANA.

Letters Patent No. 74,573, dated February 18, 1868.

IMPROVEMENT IN BOXES FOR STREET STOP-COCKS.

The Schedule referred to in these Letters Patent and making part of the same.

TO WHOM IT MAY CONCERN:

Be it known that we, HARVEY A. MOORE, E. OTIS FRINK, and SAMUEL C. FRINK, of Indianapolis, in the county of Marion, and State of Indiana, have made new and useful Improvements in Street Stop-Cock Boxes for water, gas, and other purposes; and we do hereby declare the following to be a full and exact description of the same, reference being had to the drawings that accompany and form a part of these specifications.

The object of our invention is to provide a street stop-cock box for the protection of gas and water-pipes, and for obtaining access to them at certain points.

Figure 1, perspective view.

Figure 2, sectional view, showing a flange on the inside and one on the outside.

Figure 3, under side of the cover, showing lugs by which the cover is fastened to the box.

Letter A, box; letter B, cover. We make the box cylindrical in form, with a wide flange extending around the top, as may be seen in fig. 2, at *e*, to keep it from sinking below the surface; also, a flange running perpendicular with the box, (see figs. 1 or 2,) at *f*, to keep it from turning around when the cover is put on or removed. On the inside of the box, at the top, for the purpose of holding the cover, we make circular inclined flanges, shown at *h*, fig. 2, so that the further we turn the cover in one direction, the closer it is held. At one end of these flanges we place stops *i*, to prevent the lugs *k* being carried too far or past the flanges by any means. The cover B is made to extend to the outside of the flange *e*, having on its upper side a broad lug, *L*, in the centre, by which it is operated. The cover is depressed or hollowed in the centre, so the top of the lug *L* comes on a level with the general surface. On the under side are lugs *k*, to operate on the inclined flanges *h*, and secure it to the box.

By the construction of the inclined flanges *h*, it will be readily seen that the cover can always be held tight, as the flanges or lugs become worn by use. Simply turning the cover a little further brings them to a bearing.

Most of the boxes now in use are so constructed that children and others so disposed can easily remove the cover, and carry it off, or fill the box with stones or dirt, so that when required for use, in case of fire, or otherwise, that is, to get to the stop-cock in the pipe, it has to be cleaned out, or taken out entire, which causes a great amount of trouble and delay.

What we claim, and desire to secure by Letters Patent, is—

A street stop-cock box for gas, water, or other purposes, provided with the flanges *e* and *f*, and the inclined flanges *h*, substantially as and for the purpose specified.

Also, the cover, provided with the lugs *L* and *k*, substantially as described and for the purposes set forth.
